CLAIM

The ornamental design for a programmable logic controller system module as shown and described.

DESCRIPTION

FIG. 1 is a top right perspective view of a programmable logic controller system module,

FIG. 2 is a bottom left perspective view thereof,

FIG. 3 is a top plan view thereof,

FIG. 4 is a bottom plan view thereof,

FIG. 5 is a front view thereof,

FIG. 6 is a rear view thereof,

FIG. 7 is a right side view thereof; and,

FIG. 8 is a left side view thereof.
